(57) CLAIM

The ornamental design for a wheelchair cover with a hidden pouch, as shown and described.

DESCRIPTION

FIG. 1 is a perspective view of a wheelchair cover with a pouch exposed showing the new design;

FIG. 2 is a front view of the wheelchair cover of FIG. 1;

FIG. 3 is a rear view of the wheelchair cover of FIG. 1;

FIG. 4 is a right side view thereof;

FIG. 5 is a left side view thereof;

FIG. 6 is a top view thereof;

FIG. 7 is a bottom view thereof; and,

FIG. 8 is a perspective view of a wheelchair cover with a hidden pouch showing the new design.

The indicia depicted by means of broken lines in the drawings are shown for illustrative purposes only and form no part of the claimed design.
